(57) **CLAIM**

The ornamental design for a chair mount charging station, as shown and described.

DESCRIPTION

FIG. 1 is a front, top, left perspective view of a chair mount charging station according to an embodiment of our new design, where the charging station is mounted to a chair structure;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a rear, top perspective view thereof;

FIG. 9 is a front, top, left perspective view of the chair mount charging station according to the embodiment of our new design, where the charging station is separated from the chair structure;

FIG. 10 is a front, top, left perspective view of the charging station according to the embodiment of our new design;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a rear, top perspective view thereof;

FIG. 18 is a front, top, left exploded perspective view of the charging station according to the embodiment of our new design;

FIG. 19 is a front, top, right view of a charging station, according to an embodiment of our new design, with the charger station housing shown separately in order to illustrate details of the design that would not otherwise be visible;

FIG. 20 is a left side elevational view thereof;

FIG. 21 is a right side elevational view thereof;

(Continued)

FIG. 22 is a front elevational view thereof;
 FIG. 23 is a rear elevational view thereof;
 FIG. 24 is a top plan view thereof;
 FIG. 25 is a bottom plan view thereof; and,
 FIG. 26 is a rear, top perspective view thereof.
 The broken lines shown in the Figures are for the purpose of illustrating environmental structure and portions of the chair mount charging station that form no part of the claimed design.
